UNITED STATES PATENT OFFICE

ALFRED M. MARTIN, OF CHICAGO, ILLINOIS

LATCHING MEANS FOR BINDERS

Application filed February 8, 1929. Serial No. 338,396.

This invention relates to latching means for book-type binders of the kind in which there is a pair of back members hinged together.

5 It is not broadly new to provide catch means for holding the back members spread apart to some extent in a certain type of binders, as witness the patent to Stoddard, No. 1,401,566 of Dec. 27, 1921.

10 The copending application of Harry J. Dornes, filed June 21, 1928 as Ser. No. 287,128 on latch means for loose-leaf binders illustrates, describes and claims certain structural matter shown in this present application.

15 In said Dornes application it is stated that with respect to what are known as non-shift binders the main object of his invention is to provide simple and advantageous means for holding the back members releasably in a partly-spread-apart condition; and that with respect to what is known as a shift binder the chief object is to provide means for holding the back members in such intermediate or partly-open position while per-

20 mitting one of the back members to be shifted relative to the other; and, further, that it is an object to accomplish these results by simple means, and by means so directly associated with the catch means for holding the 25 binder closed that a single manual control will suffice for both.

The objects of the present invention include those just mentioned, and the further one of providing means for releasably maintaining inoperative the means for holding the back members in the partly-open position, whereby the hinged back members of the binder may be swung freely toward and away from each other repeatedly and through 30 a wide range without manipulating a releasing mechanism each time, as is necessary according to the Dornes device mentioned.

The importance of the present improvements arises chiefly in connection with the 45 acts of inserting and removing sheets. Sometimes there are many sheets to be removed as for permanent filling, and frequently these sheet-removing-and-inserting operations are continued all day long, as where the operator 50 is posting information on the cards or sheets

by a billing or posting machine. In such case sheets here and there throughout the binder are selected, withdrawn, written upon by machine, and replaced in the book.

The Dornes disclosure mentioned serves 55 admirably where such posting is done by pen and ink directly upon the sheets without taking them out of the binder. Its use is somewhat inconvenient, however, when there is a considerable amount of insertion or removal of sheets. The means I suggest herein for overcoming such disadvantage comprise, in the specific form illustrated, provisions rendering the Dornes intermediate latch 60 slidable so as to raise it into inoperative 65 position, with means shown as a bend or kink in the spring which actuates the auxiliary or intermediate latch for holding the latch releasably in its inoperative position.

In my copending application Serial No. 70 313,397, filed October 19, 1928, I have shown other means for accomplishing the results in connection with the said Dornes device.

In the drawings Figure 1 is an end view 75 of the preferred type of binder showing the said Dornes invention applied thereto and with the back members of the binder held partly spread apart. Fig. 1 is to be assumed as containing the present invention also;

Fig. 2 is a fragmentary and broken top 80 view of the binder of Fig. 1 and with the parts in the same relative position;

Fig. 3 is a fragmentary and broken sectional view of the binder directed toward the back members, with the back members 85 fully closed. Assume the binder of Fig. 1 fully closed and then turned upside down, with certain covering or frame parts broken away. The section is substantially on the broken line 3-3 of Fig. 1. It shows the 90 mechanisms in the hollow interior of the right-hand one of the back members as viewed in Fig. 1;

Fig. 4 is a fragmentary sectional view as 95 on the broken line 4-4 of Fig. 3; and

Fig. 5 is a sectional view at the broken line 5-5 of Fig. 4.

Binders of the kind referred to are invariably provided with means for holding the back members releasably closed, as in Fig. 100

3. These locking means are shown as comprising a pair of headed leaf-like latch projections 10 rigidly secured to back member A and projecting so as to enter the openings 11 respectively in the inner wall 12 of the back member B. Mounted for sliding movement in the hollow interior of the back member B, and in the corner between the walls 12 and 15 thereof, are two angle iron pieces 13 (Fig. 3), each comprising a web 13^a lying against the wall 12 and a web 13^b resting on the wall 15, and extending over these angle iron pieces 13 are retaining brackets 14 secured as by spot-welding to the longitudinally-extending sheet metal frame part or wall 15. The top or outer surface of this plate-like frame part 15 is seen in Fig. 2 while the bottom or inner surface of it is seen in Fig. 3.

20 Each web 13^a has an opening in it adjacent to the associated latch projection 10 so that there is a part 13^{aa} thereof engaged by the head of the projection 10, as shown in Fig. 3, thus holding the two back members 25 together.

These two angle iron members 13 are connected by a thin piece of strip metal 16 spot-welded to the webs 13^b so that when the finger piece 17 (integral with the lower angle 20 iron piece 13 in Fig. 3) is pushed inward both of these members 13 are moved against the resistance of the compression spring 18 and the parts at 13^{aa} are respectively freed from the heads of the projections 10 whereby the 35 back members may swing apart on their hinge connection at 19. When the backs are brought together again the slanting surfaces respectively of the projections 10 force the members 13 longitudinally toward the compression spring 18, which spring returns the parts 13 so that both elements 13^{aa} are engaged by the heads respectively.

I have thus far described a latch device for holding the back members releasably in fully 45 closed position, the release means extending to and including the finger piece at the lower or bottom end of the binder. Those locking means do not provide for longitudinal shifting movements of the back members relatively to each other, nor do they hold the binder in a partially open position. In the shift binder they hold the back members against longitudinal shifting when the book is closed, which is an important function. This and 50 other considerations, including the small amount of space available in the hollow interior of the back members, indicate that the auxiliary means for holding the backs partly open, and for shifting movements in the shift book, should be independent of the locking means just described, although desirably under the same control.

Turning to the auxiliary latching device, note first from Figs. 1 and 2 the latch member 20 having its free end 21 turned over to

form a hook, its other end at 22 being mounted in the frame plate 15 for swinging movements of the latch member 20 by a pair of ears 23 (Fig. 5) passing through holes 24 in the plate, these ears being then bent over to form a loose connection permitting the free end 21 of the latch 20 to move away from and toward the plate 15^a. The latch member 20 is in effect bowed upward by its two flat sides 20^a and 20^b forming a ridge between them, this construction providing that the part 20^a will rest upon the frame plate 15 (see Fig. 1) thus limiting movement in that direction, and then the latch end 21 will be in position to slide over the catch 25 having the body part 25^a secured as by spot-welding on the outer surface of the plate 15^a.

From Fig. 2 note the irregular opening 28 in the latch 20. From the material originally there an integral rectangular leaf 29 is formed which in Fig. 2 is shown as passing through a rectangular opening 30 in the frame part 15. We see it emerging from the other side in Figs. 3 and 4. It has a hole through which extends loosely a spring wire 31 and the spring 31 is held rigidly at 32 by a covering and retaining plate spot-welded to frame plate 15. The tension of spring 31 is upward in Figs. 4 and 5. Its effect is to draw the latch member 20 downward in Fig. 1.

On the metal strip 16 is rigidly secured, as by spot-welding, a cam element having a base 40 (Figs. 3 and 5) and an upstanding cam part 41. In Figs. 1 and 2 it is seen projecting outwardly. It passes through a long and narrow opening 42 in frame part 15 and into a rectangular opening 43 (Fig. 2) in the latch member 20. Its slanting surface at 41^a is opposite one end of the opening 43 and it engages the metal there when the finger piece is forced inward. This action pushes the latch member 20 upward in Fig. 1 as shown by the dotted lines, thereby releasing the latch element 21 from the catch 25. The stroke of the finger piece is such as to carry the outer end of the cam 41 under the latching member 20 thus holding member 20 free of the catch 25 so long as the finger piece is held advanced.

Figs. 4 and 5 show an angle iron cleat having a web 50 spot-welded to the wall 12 and a web 51 overlying the part 40, thus holding the cam member in position.

When the latch 20 is in its operative position and the book is entirely open and the backs are then swung toward each other the latch end 21 first comes against the catch 25 and then slides over it, against resistance of the spring 31, and then the parts become caught at 21 and 25 as shown by Fig. 1. From this intermediate or partly-open position the backs can be moved further toward each other and completely closed, whereupon the locking elements 10 come into effect and hold the book

closed, in which final or closed position the latch member 20 has no holding effect.

The upward longitudinal shifting of one side of the binder or back member is permitted by spaces 19^a (Fig. 3) between the hinge lugs of the respective back members. The latching member 20 is substantially wide and the engagement at 21—25 (Fig. 2) is thus maintained during the longitudinal shifting movements of one back member relative to the other.

The importance of this intermediate-position latching, as by the latch 20, arises from the fact that when the backs are only partially spread apart, as in Fig. 1, the shifting of sheets from one set of sheet prongs 45 to the other set 46, and vice versa, to change the location of sheets through the longitudinal shifting of a back member, as on the hinge pin 19, may be done much more easily than if one side of the binder and its mass of sheet material are elevated by hand to make the prongs 45 and 46 overlap and then held in that raised position while the transverse sheet-shifting operations are being performed. With this intermediate-position latching feature incorporated the operator can manipulate the sheets from side to side and shift a back member longitudinally while permitting the binder as a whole to rest at all times in the position of Fig. 1. Entries may also be made by hand without removing the sheets.

What I have more specifically thus far described herein is the advance made by the Dornes improvement mentioned. Since that has been incorporated in the binder, at considerable expense for dies, etc., one of my problems was to embody the present invention in a form which would utilize that latch construction, and with as little additional expense as possible. The present improvements may be variously embodied, both with and without the said Dornes auxiliary latch means.

Turning now to the subject matter which is novel over said Dornes invention, note first that the holes or openings 24 (Figs. 2 and 3) are elongated, and are narrow slots or slits in the frame part 15. The more narrow strip-like pieces of metal passing through these slots 24 and terminating in the retaining ears 23 may therefore slide or shift in these slots, which means that the latch 20 as a whole may shift in the longitudinal direction of the hinge pin 19. In Fig. 2 the latch 20 would shift downward. Such shifting movement of the latch is effected by the operator's finger. He simply reaches in between the prongs and pushes the latch 20 toward his body as he is normally positioned.

Such shifting of the latch 20 causes the metal at the opening 43 (Fig. 2) to override the cam projection 41, which, being unyielding in the downward direction as viewed in Fig. 1, causes the latch 20 to rise into its

dotted line position in Fig. 1, freeing the holding elements 21—25. If the latch 20 were held in such shifted position the back members could be moved toward and away from each other throughout substantially their whole range of movement the same as if the intermediate latching device 20 were not present.

Note from Fig. 4 that the wire spring 31 has a kink or bend 60 in the path of movement of the ear 29. The latch 20 has been shifted to the left, as viewed in Fig. 4, out of its position shown in Fig. 2. In that movement the metal defining the hole 29^a in the ear 29 passed over the bump, bend or kink 60 against spring pressure. As shown in Fig. 4 the latch 20 is held by the bump 50 against casual retraction. The operator may, however, push the latch 20 in the reverse direction at any time.

The opening 30 (Figs. 2 and 3) is sufficiently enlarged to permit the latch-shifting movement mentioned.

In my said copending application the latch 20 is releasably maintained inoperative through means associated with the control 17. According to the present improvements that control remains operative both to release the catch elements 10 and to release temporarily the intermediate latch 20; but when the operator desires to maintain the latch 20 inoperative for a considerable period he sets it manually in the inoperative position where it remains until pushed back into its first position. The present construction overcomes the addition of parts and somewhat simplifies the operator's mental movements.

I contemplate as being included in this invention all such changes, departures and modifications from what is thus specifically illustrated and described as fall within the scope of the appended claims.

I claim:

1. In a binder of the character described having a pair of back members hinged together, the combination therewith of means for holding the back members releasably in closed position, means independent of said holding means for holding the back members releasably in a partially-open position, and means common to both of said holding means when said independent means are in operative position for releasing them respectively to open the binder fully, said independent means being mounted for movement by hand into and out of operative position and being free of operation by said means common to both of said holding means when moved into its inoperative position.

2. In a binder of the character described having a pair of back members hinged together, the combination therewith of means for holding the back members releasably in closed position, operating means including a finger piece for releasing said holding means,

latching means independent of said holding means for holding the back members releasably in a partly-open position, and means operatively connecting said latching means to said operating means whereby an operation of the finger piece will release said latching means when in operative position, said independent latching means being mounted for movement into and out of operative position and being free of the operation of said finger piece and associated means when in its inoperative position.

3. In a shift binder of the character described having a pair of back members hinged together and having provisions whereby one back member may shift relative to the other thereof, the combination therewith of means for holding the back members releasably in a partly-open position in all shifted positions of one back member relative to the other thereof, and means under the control of the operator for releasing said holding means when said holding means are in operative position, holding means including a member mounted for movement into and out of operative position and being free of the operation of said means under the control of the operator when out of operative position.

4. In a shift binder of the character described having a pair of back members hinged together and having provisions whereby one back member may shift relative to the other thereof on the hinge connection between them, the combination therewith of releasable holding means for maintaining the back members in partly-open position during shifting movements of one back member relative to the other thereof on their hinge connection, and means under the control of the operator for releasing said holding means, when said holding means are in operative position, whereby the back members may open fully, the arrangement being such that when the back members are moved toward each other from the fully-open position into said partly-open position said holding means will automatically again hold the back members in that partly-open position, said releasable holding means including a swinging latch member mounted for bodily movement in directions transverse of its swinging movements into and out of operative position and being free of the operation of said means under the control of the operator when so moved transversely out of operative position.

5. A latching device for a binder of the character described having back members hinged together, comprising a latch member mounted on one back member to swing in directions toward and away from the other back member, with cooperating catch means on said other back member, and means under the control of the operator for operating said latch member when in its operative position, said latch member being mounted for shift-

ing movements in directions transverse of its swinging movements into and out of operative position, there being cooperating means for holding the latch member releasably in its operative and inoperative positions respectively.
